UNITED STATES PATENT OFFICE.

JUSTUS BUTTERFIELD, OF WARREN, INDIANA.

COMBINED CURRYCOMB AND BRUSH.

1,401,134.

Specification of Letters Patent. Patented Dec. 27, 1921.

Application filed July 18, 1921. Serial No. 485,469.

To all whom it may concern:

Be it known that I, JUSTUS BUTTERFIELD, a citizen of the United States, residing at Warren, in the county of Huntington and 5 State of Indiana, have invented certain new and useful Improvements in Combined Currycombs and Brushes, of which the following is a specification.

This invention relates to implements of 10 the type employed in the care of live stock, and the primary object of the invention is to provide an improved currycomb and brush, so combined that a horse or other animal can be brushed and combed with a single 15 operation, thereby effecting a saving of time and labor.

Another object of the invention is to provide a combined currycomb and brush embodying a novel means for associating the 20 brush and the currycomb together, the bristles of the brush being so shaped as to co-operate with the currycomb and thus permit the effective use of the combined articles.

25 A further object is the provision of an improved combined brush and currycomb, embodying a brush head, a plurality of rows of brush tufts carried by the head, the active face of the tufts being inclined toward one 30 longitudinal edge of the head, a novel laterally extending plate secured to the head, and toothed bars secured to said plate and starting at the narrow portion of the brush bristles.

35 A still further object of the invention is to provide an improved combined currycomb and brush of the above character, which is durable and efficient in use, one that is simple and easy to manufacture, and one which 40 can be placed upon the market at a reasonable cost.

With these and other objects in view, the invention consists in the novel construction, arrangement and formation of parts, as will 45 be hereinafter more specifically described, claimed and illustrated in the accompanying drawing, forming a part of this specification, in which drawings:

Figure 1 is a perspective view of the improved combined currycomb and brush.

Fig. 2 is an enlarged bottom plan view of the same, and

Fig. 3 is a vertical transverse section through the improved combined brush and 55 currycomb.

Referring to the drawings in detail, where-

in similar reference characters designate corresponding parts throughout the several views, the improved currycomb and brush is designated generally by the letter A and 60 includes the brush head or back 5. This brush head or back 5 is preferably formed of solid wood, although the same of course, may be formed of other material. The lower face of the back 5 is provided with a plurality of pockets 6 for a plurality of longitudinally extending rows of brush tufts or bristles 7. The lower active faces of the rows of bristles or brush tufts 7 are gradually inclined, as at 9, toward one longitudinal edge of the brush back 5. The brush back 5 has connected thereto a laterally extending plate 8, which constitutes the back of the currycomb. This plate 8 is formed of sheet metal, preferably of a resilient nature, and extends slightly below the lower face of the brush head or back 5. The inner longitudinal edge of the plate 5 is provided with an upwardly extending flange 9, which is fitted in abutting engagement with one 65 longitudinal edge of the head or back 5. The outer end of the flange 9 is provided with an inwardly extending right angularly disposed attaching plate 10, which overlies the outer surface of the brush head or back 5. This 70 attaching plate 10 is secured to the back or head 5, by means of suitable fastening elements such as screws 11. The right angularly disposed flange 9 is secured to the longitudinal edge of the back 5 by means of 75 suitable fastening elements, such as screws 12. As shown these screws 12 are arranged relatively near the outer surface of the brush head 5, in order to permit a certain give between the laterally extending plate 8 and the back 5 if found desirable. It can be seen that the active face of the brush top 7 is inclined upwardly toward the laterally extending plate 8. The lower inner face of the plate 8 has secured thereto the toothed bars 15. As shown the toothed or 80 comb bars 15 are substantially U-shaped in cross section, and are detachably secured to the inner or lower face of the plate 8 by 85 suitable fastening elements, such as screws 12. As shown these screws 12 are arranged relatively near the outer surface of the brush head 5, in order to permit a certain give between the laterally extending plate 8 and the back 5 if found desirable. It can be seen that the active face of the brush top 7 is inclined upwardly toward the laterally extending plate 8. The lower inner face of the plate 8 has secured thereto the toothed bars 15. As shown the toothed or 90 comb bars 15 are substantially U-shaped in cross section, and are detachably secured to the inner or lower face of the plate 8 by 95 suitable fastening elements, such as screws 12. As shown these screws 12 are arranged relatively near the outer surface of the brush head 5, in order to permit a certain give between the laterally extending plate 8 and the back 5 if found desirable. It can be seen that the active face of the brush top 7 is inclined upwardly toward the laterally extending plate 8. The lower inner face of the plate 8 has secured thereto the toothed bars 15. As shown the toothed or 100 comb bars 15 are substantially U-shaped in cross section, and are detachably secured to the inner or lower face of the plate 8 by 105 suitable fastening elements, such as screws 12. As shown these screws 12 are arranged relatively near the outer surface of the brush head 5, in order to permit a certain give between the laterally extending plate 8 and the back 5 if found desirable. It can be seen that the active face of the brush top 7 is inclined upwardly toward the laterally extending plate 8. The lower inner face of the plate 8 has secured thereto the toothed bars 15. As shown the toothed or 110 comb bars 15 are substantially U-shaped in cross section, and are detachably secured to the inner or lower face of the plate 8 by

If so desired, the longitudinal edge of the brush back or head 5, which is opposite to the flange 9, can be turned arcuately as at 17, in order to conform to the configuration or curvature of the hostler's hand. In use 110 of the improved currycomb and brush, the hand is placed around the brush head and in

engagement with the plate 8 and the up-standing flange 9. The device is then used as an ordinary currycomb or brush, and the inclined surface of the brush tufts will 5 effectively aid and permit full benefit of the currycomb to be had. This combined tool will effectively curry and brush a horse, in a minimum amount of time with a minimum amount of labor.

10 Changes in details may be made without departing from the spirit or scope of this invention; but,

I claim:

1. A grooming device for animals comprising a longitudinally extending head, brush tufts carried by one face of the head, a laterally extending resilient plate carried by one longitudinal edge of the head, a plurality of longitudinally extending comb 20 bars carried by the lower surface of said plate.

2. A grooming device for animals comprising a longitudinally extending head, a plurality of rows of brush tufts carried by 25 the head, the rows of brush tufts having their active faces inclined inwardly, toward one longitudinal edge of the head, a laterally extending plate carried by the mentioned longitudinal edge of the head, and a plurality of longitudinally extending comb bars 30 carried by the inner surface of the plate.

3. A combined currycomb and brush com-

prising a longitudinally extending head, a plurality of brush tufts carried by the lower surface of the head, a laterally extending 35 plate carried by the head, an outwardly extending flange carried by one edge of the plate, an inwardly extending right angularly disposed attaching plate carried by the flange, means securing the flange and attaching plate to the head, and longitudinally extending comb bars carried by said outer face of the first mentioned plate.

4. A grooming device for horses, comprising a longitudinally extending brush 45 head, a plurality of rows of longitudinally extending brush tufts carried by the inner face of the head, the active face of the brush tufts being inclined inwardly toward one longitudinal edge of the head, a resilient 50 plate including an attaching portion, a right angularly extending attaching flange and a laterally extending carrying plate, a plurality of longitudinally extending comb bars 55 secured to the carrying plate, means securing the attaching portion to the outer face of the head, means securing the attaching flange to one longitudinal edge of the head adjacent to the outer edge thereof whereby a certain resilient movement of the carrying plate in relation to the brush head and 60 tufts will be permitted.

JUSTUS BUTTERFIELD.
